UNITED STATES PATENT OFFICE.

CHARLES L. GOODEUM, OF NEW YORK, N. Y., ASSIGNOR, BY MESNE ASSIGNMENTS, TO
WESTERN ELECTRIC COMPANY, INCORPORATED, A CORPORATION OF NEW YORK.

LOCK-OUT FOR PARTY-LINES OR EXTENSION-TELEPHONES.

1,185,086.

Specification of Letters Patent.

Patented May 30, 1916.

Application filed December 5, 1914. Serial No. 875,577.

To all whom it may concern:

Be it known that I, CHARLES L. GOODRUM, a citizen of the United States, residing at New York, in the county of New York and State of New York, have invented certain new and useful Improvements in Lock-Outs for Party-Lines or Extension-Telephones, of which the following is a full, clear, concise, and exact description.

10 This invention relates to a lock-out for party lines or extension telephones on two-wire line systems. Its object is to give a party, when he removes his receiver in using the line, a clear circuit to the central office 15 free from interruption by any other party on the same line.

The invention is of particular importance as embodied in an automatic telephone system, since it prevents interference between 20 subscribers on party lines during the time of selection.

The invention contemplates relay mechanism by which the branch in use is locked in on the common two-wire line and additional relay mechanism by which all the 25 other parties on the line are cut out.

The invention in its broadest aspect is capable of various specific embodiments, one 30 of which is shown in the accompanying drawing, by reference to which the invention may be more readily understood.

The invention is illustrated in the accompanying drawings in which—

Figure 1 illustrates the invention as applied to the subscribers of a four party line and connected to a manual office. Fig. 2 illustrates the central office connections for an automatic system, which may be substituted for the manual connections of Fig. 1.

40 Referring to the drawing, Fig. 1, A, B, C and D represent the subscribers' stations of a four-party line, the several subscribers' branches being connected to the same two-wire telephone line 1, 2. The relay mechanism for cutting out the several subscribers' branches is, in the present case, located at a common point and comprises a slow-acting relay 3 included in the line 2 and four switches 4, 5, 6, 7 controlled by said relay. 45

50 The branch lines are normally connected to the main telephone line by said switches.

The several party-lines are branched out from the common point represented by the relay 3, and individual to the branch or

party-lines are the slow-release relays 8, 9, 55 10 and 11, respectively. Each of said last-mentioned relays in its actuated position closes a corresponding switch 8', 9', 10' or 11', thus closing a path in parallel with the path which includes the switch 4, 5, 6 or 7, 60 respectively, and thereby locking the actuated individual relay to the telephone line 1, 2.

As hereinbefore stated, the invention is applicable to either a manual or an automatic telephone system. The telephone line is, therefore, shown as terminating at the central office in a jack 12, and co-operating therewith is shown a plug 13. At the central office there is also provided the usual 70 line relay 14, cut-off relay 15 and line lamp 16. The central office connections for an automatic system are indicated, in Fig. 2, the line finder being indicated at 17, and the line relay 14 being provided with a contact 75 spring 18 which controls the closure of the circuit of the starter wire 19.

The operation of the particular embodiment of the invention shown in the drawing is as follows: Let it be assumed that one 80 of the subscribers, for example, the subscriber at station B, wishes to institute a call. He removes his receiver from its hook, thereby closing a circuit as follows: from battery X at the central office, through contact 20 of cut-off relay 15, wire 2, relay 3, switch 5, wire 21, subscriber's telephone set, wire 22, relay 9, wire 1, contact 23 of cut-off relay 15, winding of line relay 14 to battery. Both the relays 9 and 3 are thereby 90 energized, but the relay 9 responds more quickly than the relay 3, and closes the switch 9', thereby maintaining the circuit closed through the relay 9, although the normal connection of the branch with the telephone line, through the switch 5, is opened by the energization of relay 3. The line of sub-station B is thus locked in. The actuation of relay 3 opens the branch lines of the other stations at contacts 4, 6 and 7, respectively, and hence none of said subscribers can interfere with the use of the common line by the subscriber whose line is already cut in.

100 The common relay 3 and the individual relays 8, 9, 10 and 11 are shown as inserted in the transmission circuit, but since said relays are of the slow-release type and may employ

a short-circuited secondary winding in the form of a copper tube, the transmission loss is inconsiderable.

Obviously this invention is not limited to the specific embodiment herein shown and described, but is capable of many variations and applications without departing from its spirit and scope.

What is claimed is:

10. 1. In a telephone system, a plurality of telephone lines, a plurality of subscribers' stations branched out from a common point on one of said lines, a relay in the line circuit at said common point, a switch controlled by said relay, an initial operating circuit, a relay individual to each subscriber's branch line, means operated by a subscriber in initiating a call which completes said initial circuit serially through the telephone line said relays and the switch controlled by the common relay, a second circuit and means operated by the individual relay to complete said second circuit through the line and said relays when the initial circuit is opened at the switch controlled by the common relay.
15. 2. In a telephone system, a plurality of telephone lines, a plurality of substations branched out from a common point on one of said lines, a relay in the line at said common point, a switch controlled by said relay, a relay individual to each subscriber's branch line, a switch controlled by and individual to each of these relays, said individual relay and said common relay being connected in series with the telephone line through the switch controlled by the common relay when the subscriber initiates a call, a switch operated by said individual relay, and a second circuit completed by said switch including said line and said relays upon the opening of the initial circuit by the operation of the switch controlled by the common relay.
20. 3. In a telephone system, the combination with a telephone line, of a plurality of branch lines normally connected to said line,

a common relay, a switch controlled by said common relay, a relay individual to each subscriber's branch line, a switch controlled by and individual to each of these relays, a circuit completed through one of said individual relays and said common relay and its associated switch upon the initiation of call, and a second circuit completed through said individual and common relays by the switch controlled by the individual relay before the circuit through the switch of the common relay is opened by the operation of said common relay.

4. In a telephone system, the combination with a telephone line, of a plurality of branch lines normally connected to said line, a common relay, a switch controlled by said common relay, a circuit completed through said common relay and said switch upon the initiation of a call, a relay individual to each branch line, a switch operated by each of said relays, and a second circuit completed by one of said individual relay switches when the initial circuit is opened at the common relay switch.

5. In a telephone system, a plurality of telephone lines, a plurality of subscribers' stations branched out from a common point on one of said lines, a relay in the line circuit at said common point, a switch controlled by said relay, a relay individual to each subscriber's branch, a circuit completed upon the initiation of a call through said common relay and its switch, a switch controlled by the individual relay, and a second circuit completing the operation by said last mentioned switch before said first mentioned circuit is opened at said first named switch.

In witness whereof, I hereunto subscribe my name this 3rd day of December A. D., 1914.

CHARLES L. GOODRUM.
